UNITED STATES PATENT OFFICE.

GUIDO WÜNSCH, OF STEGLITZ, NEAR BERLIN, GERMANY, ASSIGNOR TO ASKANIA-
WERKE AKTIENGESELLSCHAFT VORMALS CENTRALWERKSTATT DESSAU UND
CARL BAMBERG-FRIEDENAU, OF BERLIN-FRIEDENAU, GERMANY.

APPARATUS FOR REGULATING COMBUSTION.

Application filed November 25, 1927, Serial No. 235,710, and in Germany September 23, 1926.

This invention relates to an apparatus for regulating combustion. In most cases, the principle underlying combustion regulators consists in maintaining a certain ratio between the outflowing waste gases (or the inflowing volume of air) and the amount of fuel supplied. A disadvantage of this method is that the calorific value of the fuel may change (for example, when the nature 10 of the coal changes) with the consequence that the proportion of CO_2 in the waste gases is altered, so that the air is supplied in excess, or combustion is incomplete.

This disadvantage is avoided by the present invention in which the known regulation of the waste-gas-fuel ratio is supplemented by an additional regulation whereby the said ratio is varied in accordance with the proportion of CO_2 in the waste gases.

20 The accompanying drawing diagrammatically illustrates a constructional example of a regulating apparatus, as applied to a steam boiler plant according to the invention.

The boiler pressure prevailing in a steam pipe 1 is transmitted through a pipe 2 to a diaphragm 3 which is extended or contracted in accordance with the rising or falling pressure in the pipe 1. The diaphragm is provided with a contact rod 4 connected to a jet tube 5, i. e., a tube through which a medium under pressure such as compressed air or the like continuously flows. The jet tube is suitably acted upon by a spring 6 balancing the pressure within the diaphragm 3. The ends of two pipes 8 and 9 are disposed in front of the mouth of the jet tube 5 adapted to pivot about a stationary point 7, so that the compressed air or any other pressure medium discharged from said jet pipe may enter the one or the other of the pipes 8 and 9 according to the position of the jet pipe. The pipes 8 and 9 lead to chambers 10 and 11 respectively, of a differential pressure gauge, the diaphragm 12 of which is connected to a second jet tube 13 also continuously traversed by a pressure medium and adapted to pivot about a stationary point 13^a. The said pressure gauge is opposite to another differential pressure gauge 14, the two chambers of which are connected with pipes 15 and 16 respectively opening into a flue 18, one on either side of a perforated partition 17 or the like disposed therein, the waste gases, the quantity of which corre-

sponds essentially to the quantity of the inflowing combustion air flowing through the said flue. The diaphragm 19 of the differential pressure gauge 14 is connected by means of a rod 20 to a lever 21 disposed in the vicinity of the jet tube 13 and adapted to oscillate about a point 22. A sliding block 23 may be longitudinally moved (for example, with the aid of a handle 24) between the lever 21 and the jet tube 13 so that the oscillating movement of the lever 21 is transmitted to the jet pipe 13 in a variable ratio according to the position of the sliding block 23, as by the adjustment of said sliding block the lever arms of the lever 21 and the jet tube 13 vary. The ends of two pipes 25 and 26 are disposed under the mouth of the jet tube 13 and lead to the ends of a cylinder 27 respectively, the piston 28 of the said cylinder moving together with a sliding damper 29 disposed in the flue 18. The arrangement described up to this point is well known since it is disclosed in applicant's U. S. Patent No. 1,558,529.

In addition to the regulating means just described, the apparatus comprises two further differential pressure gauges 30 and 31 80 the diaphragms 32 and 33 of which are connected by rods 32^a and 33^a to a jet tube 34 adapted to pivot about a stationary point 34^a and being also traversed by a pressure medium and a lever 35 swinging about a pivot 85 35^a respectively. Between said tube 34 and lever 35 a sliding piece 36 is adapted to be moved longitudinally so that the oscillating motion of the lever 35 is transmitted to the tube 34 in a changing ratio in accordance 90 with the position of the sliding piece 36 as described above in connection with the sliding piece 23. The differential pressure gauge 31 is operated by the amount of fuel supplied; for example, in the case of a gas-fired 95 apparatus, the two pressure chambers of the gauge 31 are connected by means of pipes 38 and 39 to two points, separated by a perforated partition 47 of the fuel-supply pipe 48. In a coal-fired apparatus with a moving 100 grate, pressure in accordance with the rate of coal supply is produced by means of a pump 49 driven by the grate drive so that the air pressure produced by said pump corresponds to the velocity of the grate motion 105 and in consequence thereof also to the coal supply. In this way, one chamber of the differential pressure gauge is connected to the

pressure chamber of the said pump 49 by means of a pipe 50, while the other chamber opens to the atmosphere, as indicated in the drawing by pipe 52. The second differential 5 pressure gauge 30 is connected by two pipes 40 and 41 to the pipes 15 and 16.

Two pipes 42 and 43 are disposed under the opening of the jet tube 34 and lead to the ends of a cylinder 44 respectively, the 10 piston 45 of the said cylinder being used for controlling the supply of fuel to the furnace of the boiler. This may be done in the case of a gas-fired apparatus, for example, by means of a damper 51 inserted into the fuel 15 pipe 48 and controlled by the rod 45^a of the piston 45 and in the case of a coal-fired apparatus, for example, with the aid of a switch 46 controlling the supply of the electric current supplied to the motor driving the grate. 20 The last described apparatus therefore corresponds essentially to that first described, but, the first described apparatus serves for adapting the combustion air or the waste gases to the produced steam, while the last described apparatus serves for adapting the fuel to the combustion air or to the waste gases.

As long as the slide piece 36 rests in its position, therefore, the ratio of waste gases and 30 fuel remains constant and the supplied air and fuel remain in accordance with the produced steam.

Now, according to the invention, the said ratio should be adjusted in accordance with 35 the nature of the waste gases, especially in accordance with the proportion of CO₂ in the waste gases.

For this purpose, according to the invention, the adjustment of the sliding piece 36 40 is to be effected in accordance with the alteration of the proportion of CO₂ in the waste gases flowing through the flue 18. For this purpose, a CO₂ meter 37 of any suitable and known construction is provided, the member 45 of which, moved in accordance with the alteration of the CO₂ ratio, is connected to the slide piece 36 by means of a rod 36^a, so that said slide piece is adjusted in accordance with the oscillations of a CO₂ meter 37 connected to the flue 18 by means of the pipe 37^a.

The apparatus operates as follows: The 55 pressure prevailing in the pipe 1 acts upon the diaphragm 3 and fluctuations in the said pressure together with the spring 6 cause the jet tube 5 to oscillate one way or the other, for the purpose of varying the amount of compressed air flowing into the pipes 8 and 9 and producing a difference between the pressure in the chamber 10 and that in the chamber 11. This difference in pressure acts upon 60 one side of the jet tube 13, the other side of which is acted upon by the waste gases through the medium of the diaphragm 19 of the differential pressure gauge 14. The 65 lever 21 and the sliding blocks 23 disposed be-

tween the lever 21 and the jet tube 13, serve the purpose of adjusting the ratio of transmission of movement between the two diaphragms 12 and 19. When the thrust on one side of the jet tube 13 is greater than on the other, the said tube oscillates about its stationary pivot so that more or less compressed air flows into the pipes 25 and 26, with the result that the piston 28 moves to the right or to the left together with the 70 damper 29. As a consequence, the volume of gases flowing through the flue 18 is increased or decreased and the difference in the pressure between the two faces of the diaphragm 32 of the differential pressure gauge 80 30 is altered for the purpose of oscillating the jet tube 34. This causes the piston 45 to move to the right or to the left in order to operate the damper 51 or the switch 46 to increase or reduce the amount of fuel by increasing or 85 decreasing the speed of the grate. The ratio between the volume of air or of waste gases and the amount of fuel supplied thus remains constant at any load of the boiler provided the movement-transmission ratio between the 90 diaphragms 32 and 33 of the differential pressure gauges 30 and 31 remains unaltered, i. e. as long as the position of the sliding piece 36 is unaltered, the said position being in accordance with the oscillations of the CO₂ 95 meter 37. When, however, the proportion of CO₂ in the waste gases is altered, (for example, when fuel of a higher or lower calorific value is being burnt), the said meter moves the sliding piece 36 in one or the other direction 100 so that the movement-transmission ratio between the diaphragms 32 and 33 is altered, thereby altering the proportion of fuel supplied relatively to the volume of waste gases. Thus, in any case, combustion is complete 105 and therefore, the supply of heat is satisfactory.

Of course, the invention is not limited to the construction just described, since other suitable means may be used for maintaining 110 the ratio between the volume of air or waste gases and the amount of fuel supplied. The essential feature in any case is to alter this ratio automatically with the aid of a regulating device actuated in accordance with the 115 nature of the waste gases. This device need not necessarily be a CO₂ meter but may be a device operated by the specific weight of the waste gases, or by their proportion of CO₂, or by any of their properties.

The apparatus according to the invention may be used in conjunction with coal-fired, gas-fired, oil-fired or any type of furnaces.

I claim as my invention:

1. An apparatus for regulating combustion comprising a waste gas pipe, fuel supplying means, a further pipe through which a compressed gas flows, means adapted to move said last mentioned pipe in opposite directions corresponding to the flow of the 120 125 130

waste gases in said waste gas pipe, and the flow of fuel supplied by said supplying means respectively, means operated by the said medium escaping from said further pipe adapted to maintain a certain ratio between the flows of the fuel and the waste gases, and a device operated according to the composition of the waste gases and regulating the said ratio.

- 10 2. An apparatus for regulating combustion comprising a waste gas pipe, fuel supplying means, a further pipe through which a compressed gas flows, gauges influenced by the quantity of waste gases flowing in said waste gas pipe and by the quantity of fuel supplied by said supplying means respectively which move said last mentioned pipe in opposite directions, means operated by the said medium escaping from said further pipe and adapted to maintain a certain ratio between the flows of the fuel and the waste gases, and a device operated according to the composition of the waste gases and regulating the said ratio.
- 15 3. An apparatus for regulating combustion comprising a waste gas pipe, fuel supplying means, a further pipe through which a compressed gas flows, gauges influenced by the quantity of waste gases flowing in said waste gas pipe and by the quantity of fuel supplied by said supplying means respective-

ly which move said last mentioned pipe in opposite directions, an adjustable device arranged between one gauge and said further pipe adapted to change the ratio between the influences of the gauges on said further pipe, means operated by the said medium escaping from said further pipe and adapted to maintain a certain ratio between the flow of the fuel and the waste gases, and a device operated according to the composition of the waste gases and adjusting said adjustable device.

4. An apparatus for regulating combustion comprising a waste gas pipe, fuel supplying means, a further pipe through which a compressed gas flows, means adapted to move said last mentioned pipe in opposite directions corresponding to the flow of the waste gases in said waste gas pipe, and the flow of fuel supplied by said supplying means respectively, means operated by the said compressed gas escaping from said further pipe and adapted to maintain a certain ratio between the flows of the fuel and the waste gases, and a device operated according to the proportion of CO_2 in the waste gases and regulating the said ratio.

In testimony whereof I have affixed my signature.

GUIDO WÜNSCH.
